UNITED STATES PATENT OFFICE.

GUNNAR C. ENGSTRAND, OF BROOKLYN, NEW YORK.

BARGE.

1,403,899.

Specification of Letters Patent. Patented Jan. 17, 1922.

Application filed April 27, 1921. Serial No. 464,860.

To all whom it may concern:

Be it known that I, GUNNAR C. ENGSTRAND, a subject of the King of Sweden, residing at Brooklyn, in the county of Kings 5 and State of New York, have invented certain new and useful Improvements in Barges, of which the following is a specification.

My invention provides a composite plank supporting framing for structures of quadrilateral section like barges and pontoons.

My invention provides double flanged deck and bottom stringers resting on shouldered uprights to support the deck and bottom planking.

My invention provides diagonal one-piece tension members which receive their initial tension from the flanged deck and bottom stringers, which are kept in a sprung position over the shouldered uprights.

My invention also provides end uprights having the planes of the shoulders at their opposite ends converging, so that the initial tension in the diagonal members will be further increased when the end uprights are 25 pressed home between the flanges of the sprung deck and bottom stringers.

My invention also provides a crowned bottom and deck.

In the drawing:—

Figure 1 shows a cross section of a barge.

Figure 2 shows a fractional longitudinal section on the line A—A on an enlarged scale.

Referring to the drawing in which like reference characters designate corresponding parts, 1 represents the transverse barge frame.

The barge frame 1 comprises double flanged bottom and deck stringers 2 which 40 stringers rest upon shoulders 3 cut at the ends of the center uprights 4.

The stringers 2 are kept in a sprung position over the shoulders 3 by means of the diagonal eye bars 5 which are secured to the 45 double stringers by means of pins 6.

The end uprights 7 are furnished with shoulders 8 so inclined that the plane of the top shoulders converges toward the plane of the bottom shoulders. The end uprights 7 50 will then wedge between the sprung deck and bottom stringers 2 when being pressed outwards, and the initial tension in the diagonal eye bars 5 will be increased.

The uprights are kept in their proper positions by means of bolts 9.

At the ends the web of the flanged stringers 2 has been bent over to form a corner flange 10, to which flange the corner planks are conveniently bolted.

Planking 11 is bolted to the barge frames 60 1 in the conventional manner.

The procedure of construction is as follows:—

The double bottom and deck stringers 2 are first clamped to the ends of center up- 65 rights 4 and pressed well home against the shoulders 3.

The ends of the stringers are now sprung together and the diagonal eye bars 5 are secured to the stringers 2 by means of pins 6. 70

The end uprights are inserted and pressed well home and the bolts 9 are inserted.

The frames 1, when completed, are properly spaced and the planking 11 is bolted to them in the conventional manner, and the 75 barge is completed.

I do not wish to be understood to limit myself to the construction of barges, as other floating structures like dry dock pontoons, etc., can be readily built after the same 80 method.

I claim:—

1. In a floating structure, planking, frames supporting the planking, said frames comprising double flanged deck and bottom 85 stringers, intermediate shouldered uprights which are secured at both ends between the double flanged deck and bottom stringers which rest on the shoulders of said intermediate uprights and diagonal tension mem- 90 bers holding the double stringers in a sprung position over the shoulders of the intermediate uprights.

2. In a floating structure, planking, frames supporting the planking, said frames 95 comprising double flanged deck and bottom stringers, intermediate shouldered uprights which are secured at both ends between the double flanged deck and bottom stringers which rest on the shoulders of said intermediate uprights, diagonal tension members holding the double stringers in a sprung position over the shoulders of the intermediate uprights and end uprights having shoulders so inclined as to increase the initial tension 100 in the diagonal tension members when pressed home between the sprung deck and bottom stringers.

3. In a floating structure, planking, frames supporting the planking, said frames 110

comprising double flanged deck and bottom stringers, intermediate shouldered uprights which are secured at both ends between the double flanged deck and bottom stringers which rest on the shoulders of said intermediate uprights and diagonal tension members holding the double stringers pressed

against the shoulders of the intermediate uprights.

GUNNAR C. ENGSTRAND.
